UNITED STATES PATENT OFFICE.

MENDEL RABINOWITZ, OF NEW YORK, N. Y.

FOLDING PIN TICKET.

Application filed April 27, 1927. Serial No. 187,058.

The present invention is concerned with improvements in folding pin tickets of the character commonly employed for tagging garments, cloth, or various other articles of 5 textile merchandise.

One of the most common inconveniences encountered in connection with the use of pin tickets has been the failure to provide any efficient means for protecting the pin 10 ends. In consequence, the people handling the goods frequently scratch and tear their hands and clothing on the exposed ends of the pins, not only when removing the tickets, but in the ordinary course of handling 15 the merchandise.

A prime object of the present invention is to overcome this difficulty by the provision of a folding pin ticket so arranged that when in applied position, there will be no 20 projecting or accessible pin ends upon which persons handling the merchandise may scratch themselves.

A further object of the invention is to provide a folding pin ticket which may be 25 applied and removed with expedition and facility and without danger of scratching or pricking the fingers during the manipulation of the ticket.

Still other objects of the invention are 30 to provide a pin ticket of simple, practical construction which will be rugged, durable and efficient in use, and well suited to the requirements of economical manufacture.

With the above noted and other objects in 35 view, the invention consists in certain novel features of construction and combinations and arrangements of parts, as will be more fully hereinafter set forth and pointed out in the claims. The invention may be more 40 fully understood from the following description in connection with the accompanying drawings, wherein—

Fig. 1 is a perspective view of a pin ticket embodying the present invention prior 45 to its application to the goods to be marked.

Fig. 2 is a plan view showing the ticket in applied position.

Fig. 3 is a plan view of the blank from 50 which the ticket is formed.

Fig. 4 is a greatly enlarged transverse sectional view on the line 4—4 of Fig. 2.

The ticket of the present invention is preferably formed from a generally rectangular 55 elongated blank 10 provided with a transverse fold line 11 dividing the ticket into a pair of similarly shaped sections 12 and 13

adapted to lie on opposite sides of an article of merchandise to which the ticket is attached. The free edge of the section 13 is additionally provided with a relatively 60 short flap 14 adapted to be folded inwardly on the line 15.

Adjacent the free edge of the section 12 there is mounted a double pointed pin, the intermediate portion of which is bent as at 65 16 around the edge of the section 12, and the ends of which passed through the section 12 are inwardly offset as at 17 and terminate in a pair of pin portions 18 disposed in approximate parallelism with each other 79 and normally at right angles to the surface of the section 12.

The inwardly folding flap 14 is provided with a pair of openings 19 through which the pins 18 are adapted to pass after they 75 have penetrated the fabric 20 of the merchandise. Arranged near the free edge of the section 13 are a pair of oppositely disposed keyhole slots 21, the enlarged inner 80 ends 22 of which align with the openings 19 and permit free passage of the pins 18 therethrough.

In applying the ticket to a fabric such as 20, two sections 12 and 13 lie on opposite 85 sides of the fabric; the pins 18 pass through the fabric and through the aligned openings 19 and 22. The pins are then manually bent in opposite directions against that face of the flap 14 which lies adjacent the section 13. The keyhole slots 21 permit such bending 90 of the pins, and due to the inherent resiliency of the paper or cardboard material of the ticket, flap 14 will spring slightly away from the section 13, and the pin ends will be entirely inaccessible from the outer 95 surface of the section 13. These pin ends lie under the keyhole slots and against the face of the tab. Thus, the fabric or other article of manufacture 20 may be carelessly handled 100 without any danger of tearing the hands on the projecting ends of the pins. When it is desired to remove the pin ticket from the fabric, the operator simply grasps the two inner corners of the ticket, flexing the same transversely to expose the pins, then manually bends the pins back into approximate 105 parallelism and removes the ticket by separating the two ends of the sections 12 and 13 to withdraw the pins from the fabric.

While I have shown the slots 21 as of 110 general keyhole shape, it will be apparent that any equivalent shape might be used in

this connection, it is also to be understood that the particular manner of attaching or anchoring the pin portion of the ticket to the section 12 is subject to a wide range of variation and any conventional method of attaching the pin may be employed. The present invention is particularly concerned with the provision of the means which prevents projection of the pin ends when the ticket is applied and the merchandise handled in the ordinary manner.

Obviously, various changes and alterations might be made in the general form and arrangement of parts described without departing from the invention. Hence I do not wish to limit myself to the details set forth, but shall consider myself at liberty to make such changes and alterations as fairly fall within the spirit and scope of the appended claims.

I claim:

1. A pin ticket including generally similarly shaped sections adapted to lie on opposite sides of a fabric and hingedly connected at one edge, a double pointed pin carried by one section adjacent the free edge of the latter, an inwardly folding tab connected to the free edge of the other section, said tab having openings therein through which the pins are adapted to pass after they have

penetrated the fabric, said tab-bearing section having slots therein aligned with the openings in the tab and of sufficient length to permit the pin ends to be bent back through the slots against the face of the tab through which the pins have passed, said slots being of general narrow elongated shape with their inner ends aligned with the openings in the tabs and their other ends extending in opposite directions toward the side edges of the slotted section.

2. A fastener for tickets, envelopes or the like including a pin bearing member and a flap member, a double pointed pin carried by the pin bearing member, an inwardly folding tab connected to the free edge of the flap member, said tab having openings therein through which the pins are adapted to pass, said flap having slots therein aligned with the openings in the tab and of sufficient length to permit the pin ends to be folded back through the slots against the face of the tab through which the pins have passed, said slots being of general narrow elongated shape with their inner ends aligned with the openings in the tabs and their other ends extending in opposite directions toward the side edges of the flap.

MENDEL RABINOWITZ.
